UNITED STATES PATENT OFFICE.

HENRY BARDSLEY, OF PROVIDENCE, RHODE ISLAND, ASSIGNOR TO CROMPTON & KNOWLES LOOM WORKS, A CORPORATION OF MASSACHUSETTS.

SHUTTLE-BOX MOTION FOR LOOMS.

No. 801,503.

Specification of Letters Patent.

Patented Oct. 10, 1905.

Application filed May 13, 1904. Serial No. 207,865.

To all whom it may concern:

Be it known that I, HENRY BARDSLEY, a citizen of the United States, residing at Providence, in the county of Providence and State 5 of Rhode Island, have invented certain new and useful Improvements in Shuttle-Box Motions for Looms, of which the following is a specification.

My invention relates to shuttle-box motion 10 for looms, and particularly to that class of shuttle-box motions shown and described in my Letters Patents Nos. 626,960 and 681,648.

The object of my invention is to improve upon the construction of some of the parts of 15 the shuttle-box motion shown and described in said patents, and more particularly the master-gear, the mutilated pinions meshing therewith, the diametrical levers connected with said pinions, and the adjusting means 20 for the cranks which operate the shuttle-box levers.

In my improvements I provide a plate combined with each set of teeth on the master-gear, extending along one side or edge of the 25 teeth, with a recess therein at each end. I provide each mutilated pinion with four teeth longer than the other teeth and a diametrical lever for each mutilated pinion which does not have a pivotal motion, as shown and de- 30 scribed in said patents, but has a sliding or longitudinal motion with means for operating it. I also provide a single adjusting-screw for the crank-plate of the mutilated pinion, all as will be hereinafter fully de- 35 scribed.

I have only shown in the drawings sufficient portions of a six-shuttle-box motion for looms of the type shown and described in said patents, with my improvements combined there- 40 with, to enable those skilled in the art to which my invention belongs to understand the construction and operation of my improve- 45 ments.

Referring to the drawings, Figure 1 is a side elevation of a portion of a loom frame or side and parts of a six-shuttle-box motion with my improvements combined therewith looking in the direction of arrow *a*, Fig. 2. Fig. 2 is a plan view of the parts shown in Fig. 1 looking in the direction of arrow *b*, same figure. Fig. 3 is a side view of one of the mutilated pinions, the diametrical lever connected therewith, and the operating-lever

looking in the direction of arrow *c*, Fig. 4. Fig. 4 is a top or plan view of the parts shown in Fig. 3 looking in the direction of arrow *d*. Fig. 5 is an end view of the parts shown in Fig. 4 looking in the direction of arrow *e*, same figure. Fig. 6 is a vertical section on line 6 6, Figs. 4 and 5, looking in the direction of arrow *c*, same figure. Fig. 7 is an end view of the adjustable crank-plate and crank-pin for operating the box-levers looking in the direction of arrow *f*, Fig. 8. Fig. 8 is a side view of the parts shown in Fig. 7 looking in the direction of arrow *g*, same figure. Fig. 9 is a side view of the parts shown in Fig. 8 looking in the direction of arrow *h*, same figure; and Fig. 10 is a vertical section on line 10 10, Figs. 7 and 9, looking in the direction of arrow *i*, same figure.

In the accompanying drawings, 1 is a part of a loom side or frame.

2 is a stand or support for the several parts of the shuttle-box motion secured to the loom side 1 by bolts 2' or otherwise.

3 is the bottom or cam shaft of the loom.

4 is a mutilated driving-gear secured to the shaft 3 and adapted to mesh with and communicate an intermittent motion to a gear 5, 80 fast on the hub of the master-gear 6, mounted on a stud 2''. The master-gear 6 has in this instance four sets of teeth 6' on its periphery and also has extending along on one side or edge of said teeth a plate 6'', the outer edge of 85 which extends a little beyond the outer ends of the teeth 6'. The plate 6'' is preferably made integral with the rim of the master-gear 6; but it may be made separate therefrom and attached thereto, if preferred. At each end 90 of the plate 6'' there is a recess 6''' a little deeper than the recesses between the teeth 6. (See Fig. 1.) The master-gear 6 is adapted to mesh with and operate in this instance three mutilated pinions 7. Each mutilated pinion 7 95 has in this instance two sets of teeth 7' thereon, with a plain space between the same. The end teeth 7'' of each set of teeth 7' are slightly longer than the other teeth (see Fig. 5) and adapted to enter the recesses 6''' in the plates 6'' 100 on the master-gear 6. The recesses 6''' are the full width of the master-gear and the plate. The teeth 7' are of a corresponding width, Figs. 2 and 3. Each pinion 7 is fast on its supporting-shaft 8, which may be tubular, as shown, 105 and is mounted to rotate in suitable bearings,

and on the front face of each pinion 7 is a groove or way for a diametrical lever or bolt 9. The diametrical levers or bolts 9, which may be generally denominated "starting" 5 tooth-carriers, do not have a pivotal motion, as shown and described in said Patents Nos. 626,960, and 681,648, but have a sliding or longitudinal motion to be moved into and out of engagement with the ends of the plates 10 6" on the master-gear 6, according to the indications of the box-pattern chain. Each diametrical lever or bolt 9 has on its external surface two projections or stops 9', which are adapted to engage a block 10, in this instance 15 held by a pin 10' between the two projections 11 on the front face of each mutilated pinion 7. The engagement of the projections 9' with the block 10 limits the sliding motion of the diametrical levers or bolts 9. Each diametrical lever or bolt 9 has a slot or opening 9" 20 therein, into which extends the end of one arm of an angle-lever 12. The angle-lever 12 is pivotally mounted on a transverse pin 13, supported in the outer ends of the two projections 11 on the mutilated pinion 7. A spiral spring 14 encircles the hub of the angle-lever 12 and is fast at one end to one of the projections 11 and engages with its other end the angle-lever 12 and acts to move said 25 angle-lever 12 and through said lever to move the diametrical lever or bolt 9 into its inoperative position out of engagement with the master-gear 6. The other arm 12' of the angle-lever 12 extends in the path of an indicating- 30 finger 15. One of the two indicating-fingers 15 for one of the upper mutilated pinions 7 is fast on a rock-shaft 16, mounted in suitable bearings (see Fig. 1) and is operated through an arm 17, also fast on said shaft 16 and connections to the box-pattern chain (not shown) 35 in the usual and well-known way. The other indicating-finger 15 is loosely mounted on the shaft 16 and is operated by an arm 18 and connections to the box-pattern chain. (Not shown.) The indicating-finger 15 for the lower mutilated pinion 7 (shown in Fig. 1) is loosely mounted on a transverse rod or shaft 19 and has an arm 20 thereon and connections therefrom to the box-pattern chain, (not 40 shown,) all in the usual way and as shown and described in said Patents Nos. 626,960, and 681,648.

It will be understood that according to the indications of the box-pattern chain (not shown) 45 each of the fingers 15 for each of the three mutilated pinions 7 are operated to positively move the diametrical lever or bolt 9 into engagement with the master-gear 6 against the action of the spiral spring 14. The spiral 50 spring 14 acts to move back the diametrical levers out of engagement with the master-gear 6 when the fingers 15 are released, as shown at the left in Fig. 2.

21 is a cap which is secured to the stand 2 55 and extends around a portion of a mutilated

pinion 7, as shown in Figs. 3, 4, and 5. The cap 21 has a slot 21' therein to receive the end of the diametrical lever or bolt 9 when it is moved out of engagement with the master-gear 6, and thus lock and prevent any further 70 forward rotation or any backward movement of the mutilated pinion.

On the inner end of the shaft 8 of each mutilated pinion 7 is a disk or plate 22, which may be made integral with said shaft, as shown 75 in Fig. 10. Said disk 22 has two parallel projections or ways 22' thereon. (See Figs. 7 and 9.)

23 is a crank-plate extending between the two projections 22' and having thereon a crank-pin 24. The plate 23 has slots 23' therein and is adjustably secured to the outer face of the disk or plate 22 by two bolts 25. (See Fig. 7.)

The crank-pin 24 on each crank 23 for each mutilated pinion 7 is connected through a 80 connector 24' to the compound box-levers 26 and 27, (shown in Fig. 1,) and the compound box-levers 26 and 27 are connected to the give-way connector 28, which is connected with the box-rod 29, all in the usual and well-known 90 way.

In order to adjust the position of the crank-plate 23 and the crank-pin 24 thereon to vary the movement of the box-levers, I use a single 95 adjusting-screw 30, (see Fig. 10,) the outer end of which has an annular groove 30' therein to extend into a slot 22" in the disk 22 and the inner screw-threaded end of which passes through a screw-threaded opening in an inwardly-extending lug 23" on the crank-plate 100 23. It will be seen that by means of the single adjusting-screw 30 the position of the crank-plate 23 and the crank-pin 24 thereon may be adjusted as desired by turning said screw 30.

It will be understood that the operation of 105 the several parts of the shuttle-box motion shown in the drawings to operate the shuttle-boxes is the same as the operation of the shuttle-box motion shown and described in said Patents Nos. 626,960 and 681,648.

The advantages of my improvements will be readily understood by those skilled in the art. In the ordinary construction of the master-gear, without the plate on one side of the teeth, the teeth on the mutilated pinions are 115 liable to come into mesh with the teeth on the master-gear at the wrong time and in the wrong place through the pivoted diametrical lever sticking or the actuating-spring therefor becoming weakened or not being properly 120 adjusted. This will cause a breakage of some kind. By means of the plate extending along one side of the teeth, having the two openings 6" at each end thereof for the longer teeth 7" on the mutilated pinions 7, the mutilated pinions are not so liable to come into mesh at the wrong time or in the wrong place, and therefore the chances of breakage are 125 done away with.

The longitudinal movement of the diamet-

130

rical lever or bolt 9 of each mutilated pinion is more accurate and positive than the pivotal motion of the diametrical lever shown and described in the Patents Nos. 626,960 and 5 681,648, referred to, and it is cheaper to make, and in case of breakage of the actuating-spring 14 of the angle-lever 12 said spring can be readily replaced, which is not the case with the equivalent springs 19 and 10^a, respectively, of said patents. The employment of one adjusting-screw, as 30, and two screws to secure the crank-plate in place is simpler and cheaper than the construction shown and described in said patents.

15 I have only shown in the drawings my improvements combined with a six-shuttle-box motion; but it will be understood that my improvements may be used with a two or four shuttle-box motion of the class referred to on 20 one or both sides of the loom.

It will be understood that the details of construction of my improvements may be varied, if desired.

Having thus described my invention, what 25 I claim as new, and desire to secure by Letters Patent, is—

1. In a shuttle-box motion of a loom of the class described, the combination with the master-gear having one or more sets of teeth 30 thereon, and a plate extending along one side and beyond the peripheral ends of said teeth, and having a recess therein at each end, of a mutilated pinion having two sets of teeth thereon, and the end tooth of each set being 35 radially longer, to enter into said recess, substantially as shown and described.

2. In a shuttle-box motion of a loom of the class described, the combination with the master-gear having one or more sets of teeth 40 on its periphery, a plate extending along the side of and beyond the ends of said teeth and having a recess at each end of greater depth than said teeth, of a mutilated pinion having sets of teeth thereon, the end tooth of each 45 set being radially longer and adapted to enter into the recess at each end of the teeth on the master-gear, substantially as shown and described.

3. In a shuttle-box motion of the class described, the combination with a master-gear, 50 a mutilated pinion, of a diametrical lever or bolt having a longitudinal motion in a direction at right angles to the axis of the pinion, and means for positively moving it into operative position, and yieldingly-acting means for moving it out of operative position and means engaged by the lever or bolt when moved out of operative position by the said yielding means for locking the pinion, substantially as 55 shown and described.

4. In a shuttle-box motion of the class described, the combination with a master-gear, a mutilated pinion, of a diametrical lever having a longitudinal motion in a direction at 60 right angles to the axis of the pinion, and

means for positively moving it into operative position, said means consisting of an angle-lever with one arm engaging said diametrical lever, and a pattern-controlled indicator-finger adapted to engage the other arm of said 70 lever, and a spring for moving said angle-lever and the diametrical lever, when released by the indicator-finger, substantially as shown and described.

5. In a shuttle-box motion of the class described, the combination with a master-gear, having one or more sets of teeth on its periphery, and a plate extending along one side or edge of said teeth, with recesses in its ends at the end of said teeth, of a mutilated pinion 80 having a diametrical lever thereon movable in a longitudinal direction to engage the master-gear, and stops on said lever to limit the motion thereof, and means positively moving said diametrical lever into operative position, 85 and for yieldingly moving it in an inoperative locked position, substantially as shown and described.

6. In a shuttle-box motion of the class described, the combination with a mutilated pinion, and the shaft carrying the same, and a disk or plate on said shaft, of a crank-plate having a threaded lug and carrying a crank-pin adjustably connected to said disk or plate, and means for adjusting said crank-plate, said 95 means consisting of an adjusting-screw turning in said threaded lug, substantially as shown and described.

7. In a shuttle-box motion of the class described, the combination with a mutilated pinion, and the shaft carrying the same, and a disk or plate on said shaft, of a crank-plate having a threaded lug and carrying a crank-pin, and adjustably secured to said disk or plate by two set-screws extending through 100 slots in said crank-plate, and one adjusting-screw for adjusting the position of said crank-plate, said screw extending through said threaded lug, substantially as shown and described.

8. In a shuttle-box motion for looms, the combination with the master-gear, of the mutilated pinion, a diametrically movable starting-tooth carrier in connection with the said pinion, a spring to actuate the said carrier in 115 one direction into engagement with the master-gear, a lever acting directly to actuate the carrier in the opposite direction for such engagement, and pattern connections to operate the said lever, substantially as described.

9. In a shuttle-box motion for looms, the combination of the master-gear, the mutilated pinion, the diametrical sliding bolt, the spring actuating the bolt to engagement in one direction, the lever directly actuating the bolt to engagement in the opposite direction, and pattern connections arranged to operate upon the lever, substantially as described.

10. In a shuttle-box motion for looms, the combination of the master-gear provided with 130

- 4
- starting means for the mutilated pinion, with the mutilated pinion, the diametrical sliding bolt, the spring actuating the bolt in one direction to engagement with the starting means, and the lever directly actuating the bolt in the opposite direction, to engagement with the starting means, and pattern connections arranged to operate upon the lever, substantially as described.
  - 10 11. In a shuttle-box motion for looms the combination of the master-gear, the mutilated

pinion, the diametrical sliding bolt, the spring actuating the bolt in one direction, the lever directly actuating the bolt in the opposite direction, pattern connections arranged to operate the lever, and locking means for holding the mutilated pinion in its resting position, substantially as described. 15
